(57) **CLAIM**

We claim the ornamental design for an collapsible stroller frame, as shown and described herein.

DESCRIPTION

FIG. 1 is a side perspective view of an collapsible stroller frame, showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom view thereof.

The broken lines shown in the drawings illustrate environment and form no part of the claimed design.
